UNITED STATES PATENT OFFICE.

JOANNES PIAT, OF LYON, FRANCE.

CARBURETER-NOZZLE.

1,310,964.

Specification of Letters Patent.

Patented July 22, 1919.

Application filed November 22, 1917. Serial No. 203,433.

To all whom it may concern:

Be it known that I, JOANNES PIAT, a citizen of the French Republic, residing at Lyon, in France, have invented certain new and useful Improvements in Carbureter-Nozzles, of which the following is a specification.

This invention relates to improvements in nozzles for carbureters of explosion motors, offering certain important advantages, especially that of allowing the mathematical regulation of all deliveries of carburants, and that by means of any suitable driving-gear, placed within reach of the driver.

15 The accompanying drawing illustrates the invention.

Figure 1 is a vertical section of the device drawn to an enlarged scale.

20 Fig. 2 is an elevation thereof.

Fig. 3 is a plan view.

Figs. 4, 5 and 6 are detail views further enlarged and illustrated to explain the working of certain members.

25 Fig. 7 shows a variation of construction of the nozzle.

The nozzle is essentially composed of two concentric tubes *a* and *b*, of which *a* is rigidly mounted in the body *c* of the nozzle and *b* can be rotated around *a* by means of a 30 traction device connected to the end of a lever *d*, mounted at its base and which is displaceable in a recess *e* provided on part of the circumference of the body *c*.

The outer tube *b* is closed at the top by a 35 head *b*¹ provided with a small opening *b*², of the shape and arrangement illustrated in Figs. 3 to 6.

The inner tube is also closed at the top by a head *a*¹ which has a small opening *a*² similar to that of the tube *b* and curved to an equal radius, so that the openings coincide when the jet is to work at full feed position illustrated in Fig. 4.

40 This arrangement of openings of equal curvature and width throughout the whole of their length renders possible an admission or interception of fuel always strictly corresponding to the extent of displacement of the outer tube, by reason of regular progressive enlargement or reduction of the opening produced by this displacement. This could not be effected if the openings are circular as the area of the opening, at first reduced continues to increase up to the

full aperture and then to decrease successively.

If a single opening is considered insufficient other like openings could be provided on the heads of the tubes as shown in Fig. 7.

The regulation of the supply of fuel is obtained by varying the position of the curved opening *b*² in relation to the curved opening of the tube *a*, which is effected through the greater or lesser displacement of the outer tube *b*, by means of the lever *d*. 60 The operation of this lever is obtained by means of a suitable actuating means for instance, by means of a Bowden cable, one end of which is connected to the lever at *f*, while the other is fastened to the driving-gear 70 placed within reach of the driver's hand. Accordingly as a greater or less degree of traction is exercised at the end of the cable it will move the lever *d* forward in a corresponding manner, which by displacing the 75 tube *b* will then more or less screen the opening *a*² until it completely closes it, as shown successively by the Figs. 5 and 6.

A tension-spring *g* constantly tends to bring the tube *b* back to the position for the 80 maximum admission of fuel.

The nozzle is provided with means for regulating the extent of the displacement of lever *d*, which consists of a screw *h* (see Fig. 3) carrying a cam *i*, which will serve as 85 outermost abutment to the lever and which the driver adjusts in position beforehand.

This adjustment is effected by locking the cam in the position selected, by means of a nut; it can be further augmented by the 90 possibility of mounting the screw of the cam in other wormed holes, for instance *j* or *j*¹ provided for this purpose in the mounting plate of the nozzle.

The advantages realized by the improved 95 nozzle are essentially as follows:—

1. Almost instantaneous regulation of the carburation, by the ease with which the driver can pass through all the stages of supply of fuel, his car still going.

2. The best degree of opening of the nozzle being found, the certainty with which the driver reverts to it without any trial, by reason of the abutment of the actuating lever, against the fixed cam;

3. Facility in impoverishing the carbureted mixture up to the stoppage of the motor, if desired, this being effected either

direct or by coupling the regulator of the motor to the aforesaid actuating lever;

4. Possibility of completely stopping, at any moment, the entrance of fuel, by full traction on the actuating lever.

5. Increase or reduction of the admission of the fuel, always mathematically corresponding to the extent of displacement of the actuating lever.

10. What I claim as my invention and desire to secure by Letters Patent of the United States is:—

An adjustable nozzle for carburetors comprising a vertical jet tube in communication with the fuel supply at its lower end and closed at its upper end and having a curved fuel delivery orifice or orifices in said closed end, a tube concentric with and closely surrounding said jet tube and closed at its

upper end and having a curved slot, fuel delivery orifice or orifices at the same radius as said first mentioned orifice or orifices in its closed end, a collar at the base of said latter tube, a lever attached to said collar for rotating said latter tube upon said jet tube so as to cause said orifices to coincide or to more or less screen one another to allow passage of the fuel or to be entirely masked to cut off the supply of fuel and adjustable means for regulating the displacement of said lever.

In witness whereof I have signed this specification in the presence of two witnesses.

JOANNES PIAT.
